DANIEL N. ALLEY AND ALBERT E. MILLER, OF PERU, INDIANA.

WINDOW-SHADE FIXTURE.

1,252,982.

Specification of Letters Patent.

Patented Jan. 8, 1918.

Application filed March 8, 1917. Serial No. 153,387.

To all whom it may concern:

Be it known that we, DANIEL N. ALLEY, and ALBERT E. MILLER, citizens of the United States, residing at Peru, in the county of 5 Miami and State of Indiana, have invented certain new and useful Improvements in Window-Shade Fixtures, of which the following is a specification.

This invention relates to improvements in 10 window shade fixtures, and more particularly to shade brackets of the nailless type.

The main object of the invention is to provide a simply constructed, cheap and efficient device of this character which may be quickly applied to or detached from a 15 window frame without the use of any extraneous fastening elements and without the use of any penetrating prongs thereby avoiding mutilation or marring of the frame on 20 which it is mounted.

Another object is to construct a device of this character which may be quickly and easily adjusted to fit window frames of varying widths and on which the shade 25 brackets proper are adjustable to accommodate shade rollers of different lengths.

Still another object is to provide peculiar 30 means for connecting the adjustable parts of this fixture, said means being so constructed that the coöperating elements thereof will automatically snap into engagement and hold the parts against accidental separation, and yet permit them to move relatively to each other on the exertion of sufficient 35 force.

With the foregoing and other objects in view, which will appear as the description 40 proceeds, the invention resides in the combination and arrangement of parts and in the details of construction hereinafter described and claimed, it being understood that changes in the precise embodiment of the invention herein disclosed may be made 45 within the scope of what is claimed without departing from the spirit of the invention.

In the accompanying drawing:

Figure 1 represents a front elevation of the upper portion of a window frame with this improved fixture applied, parts being broken out for convenience in illustration,

Fig. 2 is an enlarged detail front view showing the bracket carrying strap and its connection with the fixture,

Fig. 3 is an enlarged end view of the fixture taken from the right of Fig. 1, 55

Fig. 4 is a top plan view of the right-hand end of the fixture, and

Fig. 5 is a transverse vertical section taken on the line 5—5 of Fig. 1.

In the embodiment illustrated, a supporting structure is shown in the form of two clamps C and C' designed to be secured in place on opposite sides of a window frame F, and made right and left for this purpose, but which otherwise are exactly alike and hence one only will be described in detail. 60

Each of these clamps is constructed of any suitable sheet metal finished in any desired manner and each constitutes two members, one of which is in the form of a plate 2, which has its side edges bent and folded inwardly to form guides 3 parallel with the body of the plate and in which the side edges of the other member, which is also in the form of a plate 1 are designed to slide 70 to adapt said plates to be adjusted longitudinally to fit window frames of different widths.

These plates 1 and 2 have outstruck rounded hollow nipple-like protuberances 4 and 5 80 arranged in longitudinal alinement and spaced apart any desired distance. The protuberances on one plate register when the parts are assembled with those on the other and form sockets in which are designed to 85 snap the protuberances of the inner member when brought into operative relation as is shown clearly in Fig. 5 and thereby lock the plates in adjusted position, and yet owing to the rounded construction of said protuberances will permit the plates to slide relatively to each other when forcibly moved toward or away from each other in longitudinal direction. 90

The plate 2 has its outer end bent laterally 95 rearward at right angles as shown at 6 to form an arm for engagement with the outer side edge of the facing of the window frame F. This end is then bent inwardly at right angles as shown at 7 to form an arm parallel 100 with the plate body designed to fit in at the back of the window frame facing for securely holding the plate in position against lateral movement. The arm 7 has an in-turned flange 8 at its upper edge tapered toward 105 its outer end to form a wedge to be

driven in at the rear of the window frame facing. The arm 6 is shown provided with a pair of vertically spaced transversely extending slots 9 designed to receive and support a curtain pole bracket, not shown.

The plate 2 is provided with four pairs of longitudinally extending transversely spaced slots 10, 11, 12 and 13. The slots of each pair are spaced transversely and alined 10 and the pairs 10 and 11 are transversely spaced and alined with each other while those 12 and 13 are similarly spaced and alined. These pairs of slots are designed to form keepers 14 to receive attaching tongues 15 or fingers 15 which project laterally from opposite edges at opposite ends of a bracket carrying strap 16. These fingers are offset laterally inward as shown at 15' to space the strap 16 laterally from the plate 2 on which 20 it is mounted a sufficient distance to provide for the free movement of the shade bracket proper 17 soon to be described. This strap 16 is disposed longitudinally on the plate 2 and the attaching fingers 15 thereof taper 25 toward their free ends to adapt them to have a wedge-like engagement with their keepers 14, the inner edges of said fingers being shown incline 1 and their outer edges straight, although they need not necessarily be so constructed.

Mounted to slide on each strap 16 is a shade supporting bracket 17 which is of conventional form, being provided with the usual pintle receiving aperture as 18. This 35 bracket 17 has a laterally extending attaching plate 19 at its inner end, the side edges of which are inturned to form guides 20 for slidable engagement with two opposite side edges of the strap 16. Each of these 40 brackets and straps at the opposite sides of the window frame are exactly alike except that the plate 19 of one turns outwardly in one direction and that of the other in the opposite direction as is usual in devices of 45 this character. The plate 19 of each of the brackets 17 has an outstruck hollow protuberance 21, similar in construction to the protuberances 4 and 5 above described and which is designed to form a socket and snap 50 over and yieldably engage similarly shaped protuberances 22 arranged in longitudinal alinement on the strap 16, said latter protuberances being spaced apart any desired distance to provide for the positioning of 55 the bracket 17 at any desired point thereon to adapt it to accommodate shade rollers of different lengths. It will thus be seen that by simply sliding the bracket 17 in one direction or the other that it will move over 60 the protuberances 22 with the exertion of a slight amount of force and that said protuberances will spring into and interlockingly engage the protuberance 21 carried by said bracket when relieved of said force, the 65 clamping engagement between the protuber-

ances of the two members being sufficient to hold the bracket against accidental displacement.

It is obvious that the offsetting of the fingers 15 will provide sufficient space for 70 the plate 19 of the bracket 17 to slide freely without frictional engagement with the protuberances 4 and 5 on the plate 2 which is shown disposed in close proximity to said strap 16, although it need not necessarily 75 be so disposed.

In the use of this fixture, the plates 1 and 2 of each clamp having been adjusted relative to each other to correspond to the width of the frame to which the device is to be applied and the ends of the clamping members having been engaged with the opposite edges of the frame facing in the manner above described, the brackets 17 carried by said clamps may be adjusted toward each 80 other by sliding them back and forth on the straps 16 to properly position them to receive and support a shade roller, not shown, in connection with which they are designed to be used.

It is also obvious that the straps 16 may be detached when desired, such as for the renewing of a bracket 17 should it become broken and be found necessary to substitute another therefor.

From the above description it will be clearly seen that this device while simple and efficient in construction may be quickly and easily applied or removed from the frame F, and without the use of any additional fastening elements.

From the foregoing description, taken in connection with the accompanying drawings, the advantages of the construction and of the method of operation will be readily apparent to those skilled in the art to which the invention appertains and while we have described the principle of operation of the invention together with the device which we now consider to be the best embodiment 105 thereof, we desire to have it understood that the device shown is merely illustrative and that such changes may be made as are within the scope of the claimed invention.

We claim:

1. A window shade fixture comprising two members adjustable longitudinally relative to each other and each having pairs of transversely alined spaced slots, and bracket carrying straps having fingers detachably engaged with said slots.

2. A window shade fixture comprising two members adjustable longitudinally relative to each other and each having pairs of transversely alined spaced slots, and bracket carrying straps having fingers detachably engaged with said slots, said fingers tapering toward their free ends and having a wedge-like engagement with said slots.

3. A window shade fixture comprising

two plates slidable longitudinally one on the other, one plate having its side edges in-turned to form guides to receive the edges of the other plate, the overlying plate having outstruck hollow rounded protuberances forming sockets on its inner face, the underlying plate having rounded projections on its outer face positioned to enter and yieldably engage the sockets of the overlying 10 plate whereby said plates are held in adjusted position, keepers carried by said plates, straps engaged with said keepers and having longitudinally alined projections on their outer faces, brackets mounted to slide 15 on said straps and having laterally extending attaching plates, each provided with a socket on its inner face positioned to receive one of the projections on the strap on which it is mounted, and means for detachably 20 connecting said plates to a window frame.

4. A window shade fixture comprising two plates slidable longitudinally one on the other, one plate having its side edges in-turned to form guides to receive the edges

of the other plate, the overlying plate having outstruck hollow rounded protuberances forming sockets on its inner face, the underlying plate having rounded projections on its outer face positioned to enter and yieldably engage the sockets of the overlying 25 plate whereby said plates are held in adjusted position, brackets adjustable longitudinally on said plates, each plate having at its outer end a frame engaging cap in the form of an arm extended laterally at right 30 angles from the plate end with another arm extending laterally outward from said first mentioned arm and arranged parallel with the plate, and an inturned flange at the upper edge of said parallel arm. 35

In testimony whereof we affix our signatures in presence of two witnesses.

DANIEL N. ALLEY.
ALBERT E. MILLER.
